SALAD Tosser OR SIMILAR ARTICLE

Alfred Stockli, Lontschegg, CH-8754 Netstal, Switzerland

Filed Feb. 8, 1971, Ser. No. 113,795

Term of patent 14 years

Int. Cl. D7—04

U.S. Cl. D7—99

Fig. 1

Fig. 2

Fig. 3

Fig 5

FIG. 1 is a top plan view of a salad tosser or similar article showing my new design;

FIG. 2 is a side elevational view thereof, as seen in the direction A of FIG. 1;

FIG. 3 is a front elevational view thereof, as seen in the direction B of FIG. 1; and

FIG. 4 is an underside view thereof.

I claim:

The ornamental design for a salad tosser or similar article, substantially as shown.
